(71) Applicant: **Logitech Europe S.A.**, Lausanne (CH)

* cited by examiner

(72) Inventor: **Damien O'Sullivan**, Cork (IE)

Primary Examiner — Ian Simmons

(73) Assignee: **Logitech Europe S.A.**, Lausanne (CH)

Assistant Examiner — Harold Blackwell, II

(**) Term: **14 Years**

(74) *Attorney, Agent, or Firm* — Kilpatrick Townsend & Stockton LLP

(21) Appl. No.: **29/523,875**

(22) Filed: **Apr. 14, 2015**

(57) **CLAIM**

(51) LOC (10) Cl. 14-02

The ornamental design for an input device for integrating a physical and virtual interface, as shown and described.

(52) U.S. Cl.

USPC **D14/455**

DESCRIPTION

U.S. PATENT DOCUMENTS

D678,277 S * 3/2013 Groene D14/391
D692,902 S * 11/2013 Groene D14/455

FIG. 1 is a perspective view of an input device for integrating a physical and virtual interface showing my new design;

FIG. 2 is a perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a left side elevational view thereof; and,

FIG. 8 is a right side elevational view thereof.

The broken lines shown represent unclaimed subject matter and form no part of the claimed design.
